Patented June 5, 1973

227,105

DENTAL LABORATORY MIXING MACHINE

Alan David Ellies, Frederick M. Hill, and James H. Murray, Columbus, Ohio, assignors to The Columbus Dental Manufacturing Company, Columbus, Ohio

Filed Aug. 18, 1972, Ser. No. 281,710

Term of patent 14 years

Int. Cl. D24—01

U.S. Cl. D24—1 A

FIG. 1

FIG. 2

FIG. 1 is a perspective view of a dental laboratory mixing machine showing our new design;

FIG. 2 is a top plan view;

FIG. 3 is a front elevational view;

FIG. 4 is a side elevational view; and

FIG. 5 is a rear elevational view thereof.

The side of the mixing machine not shown in the drawings is a mirror image of the side shown in FIG. 4.

We claim:

The ornamental design for a dental laboratory mixing machine, substantially as shown an described.
